DESIGN FOR A TEXTILE FABRIC

Abe Tillman, New York, N. Y.

Application April 19, 1941, Serial No. 100,517

Term of patent 3½ years

To all whom it may concern:

Be it known that I, Abe Tillman, a citizen of the United States and a resident of the city of New York, in the county of New York and State of New York, have invented a new, original, and ornamental Design for a Textile Fabric, of which the following is a specification, reference being had to the accompanying drawing forming a part thereof.

The figure is a plan view of a piece of the fabric showing my new design.

I claim:

The ornamental design for a textile fabric, substantially as shown.

ABE TILLMAN.
